UNITED STATES PATENT OFFICE.

SVEN T. NELSON, OF CHICAGO, ILLINOIS, ASSIGNOR TO SULLIVAN MACHINERY COMPANY, A CORPORATION OF MASSACHUSETTS.

CUTTING TOOL.

Application filed April 5, 1922. Serial No. 549,858.

My invention relates to cutting tools, and more particularly to cutter bits for use in the cutter chains of mining machines.

In coal mining machines of the chain cutter type, it is customary to employ a series of cutter bits, i. e. sharpened cutting elements, which are mounted in the several links of the cutter chain and so staggered relative to each other in the chain that several bits making up a group cut a path somewhat wider than the thickness of the cutter bar, each bit of the group cutting away a different path through the coal. Such bits have heretofore been largely formed by a hammering process, either by hand or by light power hammers. It has been found in practice that the bits so formed are not uniform; that their shaping is so irregular that there is almost as much wedging as cutting; that by reason of the differences in thickness at the points; wear is much more on some bits than others; and that no conception of the desirability of providing a proper clearance for the bit to the rear of the cutting portion thereof has apparently been had.

The object of my invention is to provide an improved, durable, uniform, clean cutting cutter bit and particularly to provide an improved bit in which the supporting surface for the cutting portion of the bit shall be suitably relieved in such manner as to provide for the elimination of friction between the supporting surfaces and the sides of the cut and for the ready escape of particles of material from between the sides of the bit and the material cut.

In the accompanying drawings I have shown for purposes of illustration one form which my invention may assume in practice.

In these drawings

Fig. 1 is a side elevation of the illustrative form of my improved bit in a position corresponding to that which it would occupy in a chain link.

Fig. 2 is a front view thereof.

Fig. 3 is a rear view thereof.

Fig. 4 is a section on the line 4—4 of Fig. 1.

Fig. 5 is a section on the line 5—5 of Fig. 1.

Fig. 6 is a section on plane parallel to the plane of line 4—4 of Fig. 1.

My improved bit is preferably made by a rolling process, although other methods

could be employed provided the requisite care were exercised. However, by the use of suitable stationary and moving dies it has been found possible to produce my improved bits in large quantities and in a very rapid manner.

In the illustrative embodiment of my invention it will be noted that upon the outer end of a rectangular shank 1, a cutting point 2 is formed. This cutting point presents, in the form of my bit selected for illustration, an inclined wedge-like cutting surface or face 3 which is as wide as, and in some cases slightly wider than, the thickness laterally of the shank 1 at its point of juncture 4 with the latter and which tapers as herein shown with a slight curve to a relatively sharp point 5. In its illustrative form this surface 3 makes an angle of approximately 60 degrees with the bottom of the groove which it cuts and is supported by material whose particular shape will shortly be more specifically described, but which herein makes with the bottom of the groove an "angle of relief" of approximately 30 degrees. This gives to the bit an "angle" of approximately 30 degrees.

I now desire to call especial attention to the conformation of the portion of the point 2 which supports the surface 3. From Fig. 5 it will be noted that this portion is at no point in any transverse plane parallel to the path of movement of the bit of a width equal to the width of the face 3 and so that while the face 3 is fully supported, yet due to the fact that the sides 7 and 8 of the point 2 recede or fall away towards each other from the surface 3, even though considerable wearing of the corners, i. e. the material at the lines of juncture 9 and 10 between the surface 3 and the surfaces 7 and 8, occurs, there will be no material loss of power due to the dragging of the surfaces 7 and 8 upon the sides of the groove or the development of friction by reason of the tendency for particles of material to pack between the sides 7 and 8 and the sides of the groove. The receding feature above referred to will be more easily seen by having reference to Fig. 5 which is a horizontal transverse section on line 5—5 of Fig. 1. Two parallel lines 7' and 8' lying in the same plane as indicated by line 5—5 in Fig. 1, pass adjacent the sides of the face 3, hence traces of the surfaces 7 and 8 of the cutting portion recede

from one or the other of two parallel lines 7' and 8'. In other words the cutting portion of the bit has clearance on both sides during cutting.

These bits are now believed to be best formed by a grooved rolling die or by movement of the bit bodily past a rotatable grooved die, the die being grooved to a shape to fit the outlines, the top and sides, of Fig. 4, and the relative path of die to bit or bit to die being either straight or curved, but in the general direction of the double ended arrow in Fig. 1. The die may be either slightly concave as to its side walls, in which event, as shown, the amount of stock supporting the point will be larger, or may have straight sides which would simply produce plane sides 7 and 8. In either event, due to the angle between the relative path of the bit and die and the path of the bit when cutting, the cutting face 3 of the bit will be supported by gradually tapering material and ease of cutting insured. It will here be noted that the intersection of the surfaces 7 and 8 produced will be a line so disposed that a straight line passing through any two adjacent points therein will make an angle with a line perpendicular to the length of the shank. Due to the fact that a grooved bit-forming roller is used, the traces of the bounding surfaces 7 and 8 on a transverse plane, such as shown in Fig. 4, would be the same as the traces of said surfaces on a second transverse plane, which planes have the same relation to said surfaces. Thus if the roller is made to travel in a straight path during forming of the bit, the two planes would be parallel thereby causing them to have the same relation to the surfaces. If the roller travels in a curved path during forming, the surfaces would accordingly be curved and the two transverse planes in order to have the same relation to the sides would be normal thereto or extend radially from the center of curvature of the curved path through which the roller travels. In this latter case the planes would not be parallel. These latter planes could also be equally offset from normal and still allow the required similarity between the traces on the respective planes. Any combined rectilinear and curvilinear movement of the roller or irregular movement thereof will be met by the above requirements or their equivalent. In any event the cross sectional area of the cutting portion at any two points will be the same regardless of the roller movement, due to the use of a grooved roller. It is to be understood that if the edge 2 curves from the point 5 or some intermediate point due to the fact that the metal of the bit blank did not fill out the roller groove during initial engagement of the roller with the blank, then the surfaces 7 and 8, when finished,

would have traces at least a portion of which are the same in the planes. The slight swell at the front of the bit at, and just above the juncture between the point 2 and the shank 1, results from the fact that the die groove is slightly wider at its widest point than the stock it works and as the stock accumulates in front of the die it spreads downwardly into the space between the stock and the sides of the groove. This results in a very rugged construction at the juncture of shank and point. It is of course to be understood that instead of the cutting portion terminating in a point it may terminate in a relatively straight cutting edge to form what is commonly known as a chisel point bit.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. As an article of manufacture, a coal mining machine cutter bit comprising a single homogeneous piece of material affording a shank terminating in a cutting portion having a cutting face, the material supporting said face presenting bounding surfaces whose traces on a plane parallel to the path of instantaneous travel of the bit but perpendicular to its plane of instantaneous movement recede from one or the other of two parallel lines lying in said first mentioned plane and passing adjacent the sides of the cutting face, and also having traces, at least a portion of which are the same, on any two planes having the same relation with respect to said surfaces, said surfaces being symmetrically disposed with respect to the longitudinal axis of said shank.

2. As an article of manufacture, a coal mining machine cutter bit forged from a single homogeneous piece of material affording a shank terminating in a cutting portion having an inclined cutting face, the material supporting said face presenting bounding surfaces whose traces on a plane parallel to the path of instantaneous travel of the bit but perpendicular to its plane of instantaneous movement recede from one or the other of two parallel lines lying in said first mentioned plane and passing adjacent the sides of the cutting face, and also having traces at least a portion of which are the same, on any two planes having the same relation with respect to said surfaces.

3. As an article of manufacture, a coal mining machine cutter bit forged from a single homogeneous piece of material afford-

ing a shank terminating in a cutting portion having a cutting face, the material supporting said face presenting bounding surfaces whose traces on a plane parallel to the path of instantaneous travel of the bit but perpendicular to its plane of instantaneous movement recede from one or the other of two parallel lines lying in said first mentioned plane and passing adjacent the sides of the cutting face, and also having traces, a portion of which are the same, on any two transverse planes which are normal to said surfaces.

4. As an article of manufacture, a coal mining machine cutter bit forged from a single homogeneous piece of material affording a shank terminating in a cutting portion having a cutting face, the material supporting said face presenting bounding surfaces whose traces on a plane parallel to the path of instantaneous travel of the bit but perpendicular to its plane of instantaneous movement recede from one or the other of two parallel lines lying in said first mentioned plane and passing adjacent the sides of the cutting face, and also having traces, at least a portion of which are the same, on any two transverse planes which are parallel to each other.

5. As an article of manufacture, a coal mining machine cutter bit forged from a single homogeneous piece of material affording a shank and a cutting portion terminating in a wedge-like cutting face symmetrically disposed with respect to the longitudinal axis of the shank, said bit, at points adjacent the juncture between said portion and shank, being wider than the width of the shank proper, said portion presenting bounding surfaces whose traces on a plane parallel to the path of instantaneous travel of the bit but perpendicular to its plane of instantaneous movement recede from one or the other of two parallel lines lying in said first mentioned plane and passing adjacent the sides of the cutting face, and also having traces a part of which are the same on two transverse planes which

have the same relation with respect to said surfaces.

6. As an article of manufacture, a coal mining machine cutter bit forged from a single homogeneous piece of material affording a shank terminating in a cutting portion, said bit, at points adjacent the juncture between said portion and shank, being wider than the width of the shank proper, said portion having a cutting face supported by material presenting surfaces whose traces on a plane parallel to the path of instantaneous travel of the bit but perpendicular to its plane of instantaneous movement recede from one or the other of two parallel lines lying in said first mentioned plane and passing adjacent the sides of the cutting face, and when cut by any two planes having the same relation with respect thereto have traces, at least a portion of which are the same.

7. A cutter bit forged from a single piece of homogeneous material adapted for use with a mining machine cutter chain comprising a cutting portion having a cutting face symmetrically disposed with respect to the longitudinal axis of the shank and provided with clearance, said portion having a plurality of cross sections which are substantially identical when taken so as to have the same relation with respect to the bounding surfaces of said portion.

8. A cutter bit having a shank terminating in a cutting point which has an inclined cutting face symmetrically disposed with respect to the longitudinal axis of the shank tapering laterally from its point of juncture with the shank to its outer end supported by a portion of said point which is bounded by a pair of surfaces the elements of which are parallel and make angles with the length of the shank, said surfaces diverging from a relatively narrow surface making an angle with the first mentioned surface to their juncture with said cutting face and with the sides of the shank.

In testimony whereof I affix my signature.

SVEN T. NELSON.
